(57) **CLAIM**

The ornamental design for a base for communications headset, as shown and described.

DESCRIPTION

FIG. 1 is an upper front left perspective view of a base for communications headset.

FIG. 2 is a rear elevational view of the base.

FIG. 3 is a front elevational view of the base.

FIG. 4 is a left side elevational view of the base.

FIG. 5 is a right side elevational view of the base.

FIG. 6 is a top plan view of the base; and,

FIG. 7 is a bottom plan view of the base.
